(57) **CLAIM**

The ornamental design for an inhaler grip, as shown and described.

DESCRIPTION

FIG. 1 is a front perspective view of an inhaler grip showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken line showing of the inhaler illustrates the environment of the inhaler grip and forms no part of the claimed design.
